(57) **CLAIM**

The ornamental design for an adjustable and configurable bent door pull assembly as shown and described.

DESCRIPTION

FIG. 1 is a front, top, and left side perspective view of an adjustable and configurable bent door pull assembly, showing my new design;

FIG. 2 is a front, top, and right side perspective view thereof; FIG. 3 is a front, bottom, and left side perspective view thereof;

FIG. 4 is a front, bottom, and right side perspective view thereof;

FIG. 5 is an elevational front view thereof;

FIG. 6 is an elevational rear view thereof;

FIG. 7 is an elevational left side view thereof;

FIG. 8 is an elevational right side view thereof;

FIG. 9 is an elevational top view thereof;

FIG. 10 is an elevational bottom view thereof;

FIG. 11 is a front, top, and left side perspective view of the detachable standoff with offset of the adjustable and configurable bent door pull assembly, shown separately to show aspects of the design that are not visible when combined; FIG. 12 is a front, top, and right side perspective view thereof;

FIG. 13 is a front, bottom, and left side perspective view thereof;

FIG. 14 is a front, bottom, and right side perspective view thereof;

FIG. 15 is an elevational front view thereof;

FIG. 16 is an elevational rear view thereof;

FIG. 17 is an elevational left side view thereof;

FIG. 18 is an elevational right side view thereof;

FIG. 19 is an elevational top view thereof;

FIG. 20 is an elevational bottom view thereof; and,

FIG. 21 is a sectional view taken along A-A of FIG. 19.
